NECKWEAR DISPLAY RACK

Howard B. Stern, Milwaukee, Wis.

Application May 28, 1941, Serial No. 395,644

4 Claims. (Cl. 223—82)

The present invention relates to improvements in neckwear display racks.

The primary purpose of the invention is to provide a display rack comprising a wire frame form which is adapted to support a necktie of the four-in-hand type so that the knot portion of the tie will be wrapped around an extension on the frame form and the tie will be displayed in a unique manner.

A further object of the invention is to provide a display rack for neckwear which is adapted to support a four-in-hand tie in a vertical or inclined position in its tied form.

A still further object of the invention is to provide a display rack for neckwear which is formed of a U-shaped piece of wire adapted to be inserted endwise in the necktie so that the form will engage the edge creases of the tie and hold the same extended throughout its flat portion so that when a knot is formed in the tie and wrapped around the extension of one of the U-shaped arms, the display will have the appearance of a necktie being worn.

A still further object of the invention is to provide a neckwear display which may include a series of wire frame units placed vertically or angularly so that a proper display of the tie may be had.

Other objects and advantages of the invention will become apparent during the course of the following description of the accompanying drawings, wherein,

Figure 1 is a front elevational view of the invention illustrating the display rack unit and showing the manner in which a four-in-hand tie is supported thereby:

Figure 2 is a perspective view illustrating one of the rack units, and showing the goose-neck connection at the lower end for attachment to a suitable base;

Figure 3 is a vertical cross-sectional view illustrating the manner in which the frame unit may be supported by a ball and socket swivel connection to a base;

Figure 4 is a front elevational view illustrating a modified form of the invention, wherein the frame units are bolted or otherwise secured to a base;

Figure 5 is a front elevational view of a modified form of the invention showing a differently formed tie frame unit and illustrating the manner in which the unit is secured to the base of Figure 4;

Figure 6 is a perspective view of the modified

form of the invention, illustrating the offset supporting arm thereof; and

Figure 7 is a front elevational view of a tie rack illustrating the invention in Figures 1, 2 and 3 showing the manner in which the tie may be supported at various inclined positions.

In the drawing, wherein for the purpose of illustrating a preferred embodiment of the invention, and wherein like reference characters will be employed to designate like parts throughout the same, attention is directed to Figures 1, 2, 3 and 7, wherein the reference character 5 will generally be employed to designate a tie rack unit comprising a U-shaped frame having a base portion 6 and upwardly and inwardly extending arms 7 and 8. The arms are slightly curved so that when the arms are inserted in a necktie, the tie will assume a slight curvature.

Formed on the extreme upper end of the curved arm 8 is an offset portion 9, providing a knot forming connection 10, which is adapted to receive the knot K of a four-in-hand tie A, as clearly shown in Figure 1. The knot K may receive the knot-forming portion 10 after the tie has been slipped over the upwardly and inwardly curved arms 7 and 8.

Formed intermediate the ends of the base 6 is an extension 11, having a goose-neck portion 12, the lower end of which is screw threaded 30 as at 13 so that the tie-rack may be supported in offset relation with respect to the supporting base. As illustrated in Figures 1, 2, 3 and 7, the threaded end 13 of the goose neck 12 is provided with a spherical ball member 14 which is 35 adapted to be received in a socket member 14a having a suitable set screw 14b so that the spherical ball member 14 may be adjusted to position the tie at an inclined angle with respect to a base member 16, as shown in Figure 7. The 40 spherical socket member 14a is formed integral with the upper end of a rod 15, the lower end of which is threaded or otherwise secured to the base 16.

In Figures 4, 5 and 6 a modified form of the 45 invention is shown and the necktie form is substantially identical to the form shown in Figures 1, 2, 3 and 7, and comprises a display frame, generally indicated by the reference character 20, including a base portion 21, having upwardly and inwardly directed arms 22 and 23 for receiving the necktie A. The arm 22 is provided adjacent its upper end with an offset portion 24 terminating in an extension 25 for receiving the necktie knot K, after the tie has been tied in a four-in-hand fashion.

Intermediate the ends of the base member 24 is an extension 26 having a downwardly extending angular portion 27 terminating at its free end in a screw threaded portion 28. A base 29 formed of a channel-shaped strip of metal may be provided for supporting the neck-tie rack by threading nuts 30 and 31 on the screw threaded portion 28 on opposite sides of the channel-shaped base member 29 after the screw threaded free end 28 has been passed through an opening therein.

In forming a display, as shown in Figure 4, a series of units 20 may be arranged to produce the effect of a staggered display. Also, if desired, the units 5 may be combined with the units 20 so that certain tie racks will be inclined, while others will assume a vertical position. Many unique displays may be made up from a combination of both forms of the invention and it is obvious that by so doing, neckties may be displayed to meet the aesthetic sense of the consumer.

From the above detailed description of the invention, it is to be noted that minor changes may be made therein without departing from the spirit and scope of the invention as claimed.

What is claimed as new is:

1. In a neckwear display rack, a wire frame of substantially U-shape and having side legs rising from a straight bight, said legs normally converging towards their free ends and terminating in spaced relation, an extension on the free end of one of said legs directed toward the longitudinal axis of the rack and then outwardly in line with said axis, the converging legs adapted to assume a natural unstretching position within the streamer portion depending from the knot zone of a four-in-hand necktie while the extension on one leg is disposed centrally of the knot, and an offset arm carried by the bight of the wire frame for the mounting of the rack upon a support.

2. In a neckwear display rack, a wire frame of substantially U-shape and having side legs rising from a straight bight, said legs normally converging towards their free ends and terminating in spaced relation, an extension on the free end of one of said legs directed toward the longitudinal axis of the rack and then outwardly

in line with said axis, the converging legs adapted to assume a natural unstretching position within the streamer portion depending from the knot zone of a four-in-hand necktie while the extension on one leg is disposed centrally of the knot, an offset arm carried by the bight of the wire frame for the mounting of the rack upon a support, and an adjustable mounting for the offset arm whereby the rack may be set at an inclination for display purposes.

3. In a neckwear display rack, a wire frame of substantially U-shape and having side legs rising from a straight bight, said legs normally converging towards their free ends and terminating in spaced relation, an extension on the free end of one of said legs directed toward the longitudinal axis of the rack and then outwardly in line with said axis, the converging legs adapted to assume a natural unstretching position within the streamer portion depending from the knot zone of a four-in-hand necktie while the extension on one leg is disposed centrally of the knot, an offset arm carried by the bight of the wire frame for the mounting of the rack upon a support, and a universal mounting for the offset arm whereby the rack may be set at different inclinations for display purposes.

4. In a neckwear display rack, a wire frame of substantially U-shape and having side legs rising from a straight bight, said legs normally converging towards their free ends and terminating in spaced relation, an extension on the free end of one of said legs directed toward the longitudinal axis of the rack and then outwardly in line with said axis, the converging legs adapted to assume a natural unstretching position within the streamer portion depending from the knot zone of a four-in-hand necktie while the extension on one leg is disposed centrally of the knot, and an offset arm carried by the bight of the wire frame for the mounting of the rack upon a support, said offset arm being threaded at its outer end, a base support having an opening therein through which the end of the offset arm extends and nuts threaded on the offset arm at opposite sides of the base support for engagement with the latter to hold the rack in position on the base support.

HOWARD B. STERN.
